CLAIM

The ornamental design for a telecommunications handset, as shown and described.

DESCRIPTION

FIG. 1 is a rear, top, and right perspective view of the telecommunications handset showing our new design; FIG. 2 is a rear elevational view of the telecommunications handset;

FIG. 3 is a front elevational view of the telecommunications handset;

FIG. 4 is a top view of the telecommunications handset; FIG. 5 is a bottom view of the telecommunications handset; FIG. 6 is a right side elevational view of the telecommunications handset;

FIG. 7 is a left side elevational view of the telecommunications handset; and,

FIG. 8 is a rear, bottom, and left perspective view of the telecommunications handset.

The broken line showings in the drawing views are for illustrative purposes only and form no part of the claimed design.
